UNITED STATES PATENT OFFICE.

EDWARD A. JOHNSTON, OF CHICAGO, ILLINOIS, ASSIGNOR TO MCCORMICK HARVESTING MACHINE COMPANY, OF CHICAGO, ILLINOIS.

GRAIN-BINDER.

SPECIFICATION forming part of Letters Patent No. 710,781, dated October 7, 1902.

Application filed March 5, 1901. Serial No. 49,748. (No model.)

To all whom it may concern:

Be it known that I, EDWARD A. JOHNSTON, a citizen of the United States, residing at Chicago, county of Cook, State of Illinois, have 5 invented certain new and useful Improvements in Grain-Binders; and I do hereby declare the following to be a full, clear, and exact description of the invention, such as will enable others skilled in the art to which it 10 appertains to make and use the same.

The invention relates to that part of the mechanism of a self-binder for grain-harvesters, corn-harvesters, and the like which has to do with throwing the binder devices periodically into and out of operation for the 15 purpose of binding the bundle and discharging it from the machine when bound.

The objects in view are to throw the binder devices into action as promptly as possible 20 on the actuation of the trip, so as to make an immediate separation of the gavel from the stream of grain moving toward the binder and to relieve the bound bundle of the resistance to its outward movement that is offered 25 by the upward pressure of the trip-arm, so as to facilitate the discharge of the bundle from the machine; also, to provide an improved chock for preventing the rebound of the binder devices when thrown out of operation.

30 The improvements are illustrated in the accompanying drawings, wherein—

Figure 1 is an end elevation of the principal operative parts of the binder, the crank-disk on the knotter-shaft being broken away 35 to show the internal construction of the bevel-gear beyond. Fig. 2 is an enlarged sectional detail of some of the same parts, showing the driving-dog and the trip-stop. Fig. 3 is a side view, partly in section, of the parts shown in 40 Fig. 1. Fig. 4 is a horizontal view of Fig. 1 on the line 4-4, and Fig. 5 is a sectional detail showing the chock for preventing the rebound of the binder.

Referring to the views, the binder-frame is 45 of the usual construction and, as indicated in Fig. 3, is composed of the vertical post a , the upper horizontal member a' , overhanging the binder-deck, and the horizontal member a'' , underlying the deck in the ordinary 50 manner.

The knotter drive-shaft b is journaled, as usual, in the overhanging arm a' of the binder-frame and is rotated periodically by means of a gear c^{10} , which is loosely mounted on the end of the knotter drive-shaft, as indicated 55 in Fig. 3, and is continuously driven from the packer-shaft beneath the deck by a chain or shaft in a manner that is now well understood. The wheel c^{10} is concaved or hollowed out on its outer side and is provided with 60 notches or projections c^3 around the periphery of this hollow or concave. On the extreme end of the knotter drive-shaft is fixed a crank-disk d . An arm d' projects radially from this disk and is connected, by means of the 65 link-rod c^8 , with an arm c^2 on the shaft c of the needle c' , which underlies the binder-deck, this mechanism serving to operate the needle from and by means of the knotter drive-shaft in the ordinary manner. 70

The packer-shaft b' and its pinion b^2 are continuously in rotation, and the wheel c^{10} being geared thereto, as above described, is also continuously driven. The knotter drive-shaft is periodically connected to and disconnected from the wheel c^{10} by means of a dog 75 c^4 , which is pivoted upon a stud d^6 , projecting from the inner face of the crank-disk d . As shown in Figs. 1 and 3, this disk corresponds substantially in diameter with the concaved 80 part of the wheel c^{10} , so as to cover, protect, and conceal the notches c^3 and the dog to be hereinafter described. The inner end of the dog c^4 projects into the hollow of the wheel c^{10} and carries a small roller c^5 , adapted to engage 85 the notches c^3 , so that when the roller engages in one of the notches the crank-disk and the knotter drive-shaft are rotated with the wheel. The dog c^4 is provided with a spring d^8 , which reacts between its inner end 90 and the hub of the crank-disk for the purpose of throwing the roller automatically into engagement with the wheel c^{10} .

The mechanism for tripping the binder is what is known as the "table-trip" type, and 95 consists of a plate or arm e , projecting radially outwardly from one end of a shaft e' , that is journaled in lugs or ears e^6 on the binder-frame. An arm e^2 projects from the opposite end of the trip-shaft and is connect- 100

ed by means of a link e^4 with a trip-stop consisting of a rod d^2 , that is arranged to slide vertically in and through a housing d^3 , formed on the vertical post a of the binder-frame. 5 The upper end of this trip-stop projects into the path described by the outer end of the dog c^4 as the latter rotates with the crank-disk, so that the inner end of the dog is thrown out of engagement with the notches of the 10 wheel c^{10} when its outer end strikes the stop, thereby releasing the knotted drive-shaft from the wheel c^{10} and bringing the binder to rest. The extremity of the outer end of the dog c^4 is preferably forked or notched, as 15 shown at c^6 in Fig. 5, for the purpose of more effectually and surely engaging the trip-stop. The trip-arm e is held slightly above the surface of the deck by means of a spring d^4 , inclosed in the housing d^3 and encircling the 20 trip-stop d^2 . This spring reacts between the bottom of the housing and a collar d^9 near the upper end of the stop-rod, thereby pulling up on the arm e^2 of the trip-shaft and holding the trip-arm normally above the deck, 25 as just described. For the purpose of regulating the amount of pressure required to operate the trip-arm the spring d^4 is made adjustable in tension by means of a stud d^5 , which is screwed into the bottom of the housing 30 d^3 and through which the trip-stop rod d^2 slides freely, and in order to provide for timing the action of the trip the connection between the lower end of the rod and the link e^4 is made by means of a block e^5 , which is 35 made adjustable on the lower end of the rod and is held in any position thereon by means of a nut d^7 .

The compressor-finger is denoted by g , and its supporting-arm is indicated at g' . The 40 compressor-arm is mounted on a short shaft g^2 , which is journaled in brackets h h , cast on the underlying arm a^2 of the binder-frame. The present invention is not, however, concerned with these parts of the binder, and no 45 further description of them is deemed necessary.

As is well understood, the trip-arms of the table-trip type are actuated by the downward pressure of the bundle of grain reacting 50 against the breast-plate which shields the knotted mechanism above, and the spring d^4 keeps the arm e pressing upwardly against the bundle, even after the binder has been tripped. This has the effect of opposing the 55 free discharge of the bundle to the extent of the resistance offered by the spring. It is desirable, however, that at the moment of discharge of the bundle there should be no hindrance to its outward movement, and the 60 present invention contemplates means for holding the trip-arm down after it has been actuated and rendering the spring temporarily inoperative. This arrangement consists of an arm f , secured to the needle-shaft c and 65 having a roller f' at its outer end in connection with an extension e^3 of the arm e^2 from

the trip-shaft. This extension e^3 projects into the path described by the roller f' as the arm f moves downward when the needle ascends. This action is clearly indicated in 70 dotted lines in Fig. 1, from which it will be understood that when the needle rises to present the twine to the knotted the trip-arm e is held down below the surface of the deck and the spring is prevented from returning 75 it until the needle descends again and the roller f' runs off the extension e^3 .

When the binder has been tripped into action, it operates very rapidly, and the parts have so much momentum that when the dog 80 c^4 strikes the trip-stop d^2 , thereby throwing the binder out of operation, there is considerable liability of the mechanism rebounding. In order to prevent this, I provide a chock consisting of a lug or projection i^3 on the 85 housing d^3 , and in an extension of the arm d' , which projects from the crank-disk d , as before described, I mount a roller i' , which slides in a guideway i^4 in the arm i and is pressed yielding outward by means of a spring i^2 . 90 The projection i^3 is preferably wedge-shaped or inclined on one side, so that as the arm d' rotates in the direction of the arrow in Fig. 1 the roller i' may ride over its upper surface and fall behind it, the rear side of the projection being shaped so as to form a chock or abutment preventing the return movement of the roller, and thus locking the parts against rebound.

The construction being as above described, 100 it will be noted that the trip has a very prompt action, the trip-stop requiring but little movement in order to release the dog and throw the binder into operation, and, further, that the adjustability of the connection between 105 the stop and trip-shaft crank enables the timing of the tripping action and the extent of movement of the stop, so that the needle can be set to make an immediate separation of gavel from the mass of grain coming into the 110 binder from the elevator.

Having thus described my invention, what I claim and desire to secure is—

1. In a self-binder, the combination of a 115 table-trip, a shaft to which said trip is secured, a trip-stop, a crank on the trip-shaft connected to said stop, the needle-shaft, and a projection on the latter to engage the trip-shaft crank and hold the table-trip down until the bundle is discharged.

2. In a self-binder, the combination of a trip-arm, a shaft on which the arm is mounted, a crank on the end of the shaft, a housing on the vertical post of the binder-frame, a trip-stop sliding through said housing, a 125 spring encircling the stop and holding its upper end normally above the housing, a collar on the stop to limit its upward movement, and an adjustable stop in the bottom of the housing between which and the collar the 130 spring reacts, and a connection between the trip-stop and the crank on the trip-arm shaft.

3. In a self-binder, the combination of the knotter drive-shaft, a crank-arm on said shaft, a lateral projection extending out from the vertical post of the binder-frame across the vertical plane of the crank-arm, and a radially-yielding spring-pressed roller carried by the arm and engaging the projection so as to permit the drive-shaft to revolve in one di-

rection and prevent its revolution in the opposite direction.

In testimony whereof I affix my signature in presence of two witnesses.

EDWARD A. JOHNSTON.
